UNITED STATES PATENT OFFICE.

LIBORIO G. GIARDINO, OF CAMPELLO, MASSACHUSETTS.

LOCK.

1,171,425.

Specification of Letters Patent.

Patented Feb. 15, 1916.

Application filed June 22, 1915. Serial No. 35,659.

To all whom it may concern:

Be it known that I, LIBORIO G. GIARDINO, a citizen of the United States, and resident of Campello, county of Plymouth, State of Massachusetts, have invented an Improvement in Locks, of which the following description, in connection with the accompanying drawing, is a specification, like characters on the drawing representing like parts.

This invention relates to improvements in locks and the principal object thereof is to provide a doubly secured lock in which one of the locking members may be operated from a single key and a second locking member operated from one or more different keys, while both locks may be operated by a single special key.

A further object of the invention is to provide a lock in which the key does not pass through the door member which supports the lock and in which the special key only may be utilized to unlock or lock the door from the opposite side from the one which is ordinarily utilized and which is accessible to two or more persons. The utility of such a lock will be obvious when it is considered that an employer may desire to permit one or more employees to have access to a room or safe but which room or safe the employer desires to be able to lock in such a manner that access even to the trusted employees may be barred. This is accomplished in the present invention by a single lock adapted to be embedded in the door, said lock having two bolts or series of bolts adapted to be actuated independently by different keys or simultaneously by a single or master key, the lock being also provided with a latch adapted to be projected by a spring into the usual position when one or both of the bolts are withdrawn from locking position.

Another feature of the invention is providing means whereby the mechanism which actuates the latch from the door handle will be disengaged from the door handle or knob in such a manner that the latch may not be operated when the door is locked.

Other objects of the invention will more fully appear from the following description and accompanying drawings and will be pointed out in the annexed claims.

In the drawings; Figure 1 is a plan view of a lock embodying one of the preferred forms of my invention the covering plate

having been removed, Fig. 2 is a vertical sectional view thereof on lines 2—2 Fig 1, Fig 3 is a detail view showing the key and the recess therefor in the rotary members which actuate the different locking mechanisms, Fig. 4 is a detail view of the latch illustrating the manner in which it is supported by one of the bolts which lock the door so that when the lock is projected into locking position the latch is removed from operative relation to the door knob.

In the preferred embodiment of the invention disclosed the frame for the lock comprises the usual upper and lower plates 1 and 2, the lower plate 1 serving as a base upon which the bolts and the mechanisms for actuating the same are mounted. The bolts comprise a main locking bolt 3 and an auxiliary locking bolt 4, the main bolt 3 being operable from a single or master key which is adapted simultaneously to unlock both bolts and the auxiliary bolt 4 being adapted to be actuated by a plurality of keys differing from the main or master key. The main bolt 3 as illustrated herein comprises a rectangular locking member or end provided with a preferably integral rearwardly extending rack 5 the rack being located between two guides 6 and 7. The rack 5 is actuated to thrust the bolt 4 forward to locking position and backward to unlocked position by a gear 8 which is pivotally mounted upon a preferably hollow stem 9 having a slot connecting with a suitable irregular slot 10 which may be engaged by the key. Suitable mechanism is provided for retaining the bolt in locked or unlocked position which will hereafter be more fully described.

The auxiliary bolt 4 is desirably in the form of a channel shaped member adapted to receive and to provide a guideway for the latch 11. The latch 11 is formed with a rigid head having a beveled portion 12 with two parallel members 13—14 extending rearwardly therefrom and having at their ends projecting lugs 15, 16 which are engaged by a rotatable latch actuating member 17.

The latch actuating member 13 preferably is in the form of a cylindrical stud having cam lugs 18, 19 adapted to engage the lugs 15, 16 upon the latch member, the member 17 being rotatably mounted in a socket in the auxiliary bolt 4. The latch 11 is normally retained in outwardly projected posi-

tion by a spring 21 which is seated at one end against the inner face 22 of the latch head and at the opposite end upon a lug 23 projecting upwardly from the bottom portion of the channel bar and having a forwardly extending cylindrical pin 24 to retain the spring in proper position. A similar guiding pin for the spring 25 may if desired be formed integral with or secured 10 to the head 22.

The actuating member 17 and the latch are normally held in operative position since the spring 21 pressing against the inner face of the latch head 11 normally retains the 15 latch in outwardly projected position so that the lugs 15, 16 at the rear end of the arms 13, 14 engage the cams 18, 19 upon the latch actuating member. The end of the latch actuating member 17 may be provided 20 with a gear 26 adapted when the auxiliary bolt is in retracted position as illustrated in Fig. 1 to engage a gear 27 upon the stem 28 of the usual knob.

It will be obvious from the construction 25 above described that when the auxiliary bolt 4 is in retracted position the turning of the knob will cause, through the gears 27, 26, the rotation of the latch actuating member 17 so that the latch may be withdrawn 30 and the door opened in the usual manner, but that if the auxiliary bolt 4 is moved forwardly, by mechanism which will now be described, the latch actuating member will be carried forward with the auxiliary 35 bolt so that the gear 26 upon the actuating member will be removed from the gear 27 of the knob thus permitting the knob and its stem to rotate freely out of operating relation to the latch. It will thus be ob- 40 visible that the rotation of the handle cannot be utilized by anyone tampering with the door to aid in unlocking the same. Furthermore if the key is only partially turned so that the auxiliary bolt 4 would not be thrust 45 fully into the locking recess of the door casing the door could not be opened by turning the knob since the projected latch would engage the casing, thus insuring the secure locking of the door against opening.

50 The auxiliary locking bolt 4 as before stated is preferably channel shaped in form and the outer side of one of the walls of the channel is provided with a rack 280 which is engaged by a gear 29 of smaller diameter 55 than the gear 8, rotatably mounted upon the sleeve 9 which also serves as a pivot for the gear 8. The gear 29 is provided with an annularly disposed key slot 30 the inner portion of which desirably conforms to that of the slot 10 in the gear 8. The outer end 60 however of the slot 30 projects at a greater distance from the axis and is of any special construction adapted to receive a key which may be duplicated with difficulty. 65 By this construction it will be observed that

a master key such as that illustrated in Fig. 3 may be adapted to engage and actuate both of the racks.

In actuating the lock the cylindrical sleeve 31 of the master key enters both gears 70 29 and 8. The bit 32 first engages the slot 30 so that as the key is turned it rotates the gear 29 advancing the auxiliary bolt 4 partially into locking position. When the gear 29 has been rotated one quarter of a 75 revolution the slot 30 comes into registry with the slot 10 so that the key may be thrust farther inwardly so that the portion 80 32 of the bit will engage the gear 8 and thereafter rotate the gears 29 and 8 in unison until both bolts have been projected into locking position. It will be obvious that the main bolt 3 will be advanced more rapidly than the auxiliary bolt by reason of the fact that the gear 8 is of larger diameter than the gear 29 and these gears are 85 so proportioned that when the key has made one half revolution both the main and auxiliary bolts will be thrust outwardly the same distance beyond the edge of the lock 90 casing.

It will be noted that the bit 32 of the master key is provided with a long extension 33 which engages only the smaller gear 29 and cannot be thrust into the gear 8. It 95 therefore follows that another person may be provided with a key having the long extension 32 only by which he may be able to manipulate the auxiliary bolt 4 but cannot actuate the main bolt 3.

In order to provide means for securely locking the main bolt 3 in extended or retracted position so that the same may not be withdrawn or actuated without the use of the master key I have provided a system 100 of gearing and locking racks therefor which will positively prevent improper actuation of said main bolt. To this end I have provided a series of gears 34, 35, 36, 37, 38 which are entrained with the larger gear 8 105 which engages the rack 5 of the main bolt, a locking rack 39 meshing with a gear 37 being guided by a yieldable support 40 in such a manner that it may be caused to engage also the teeth of the gear 38 when the bolt is thrust into locking position and retain the bolt in such position until released by the action of the master key. The guide 40 as illustrated herein is pivoted upon a stud 41 and is normally held in gear en- 110 gaging position by a spring 42 which may be in the form of a helical spring seated against a stud 43 extending upwardly from the face plate 1 and at its other end bearing against the end 44 of the guide 40. The op- 115 posite end 45 of the guide is engaged by a plunger 46 mounted in suitable guides 47, 48 which plunger is actuated by a cam 49 extending upwardly from the face of the outer gear 8. The cam 49 is provided with 120

100

105

110

115

120

125

130

two faces, 50 and 51. The cam face 50 is so positioned that its end normally remains in engagement with the end of the plunger 46 when the main bolt is retracted. When 5 however the main bolt actuating gear 8 is rotated by the master key the cam face 50 will thrust the plunger 46 outwardly so that the rack 39 which is actuated from the gear 37 will be moved out of mesh with the teeth of the gear 38. When the main bolt has 10 reached its forward position the end of the plunger 46 will advance over the shorter cam surface 51 permitting the rack 39 to be forced by the spring 42 into engagement 15 with the teeth of the gear 38 thus simultaneously locking into the teeth of the gears 37, 38 which meshing together are securely locked from movement in either direction. When the bolt is to be unlocked the first 20 movement of the gear 8 will cause the plunger to ride upon the cam surface 51, thus forcing the plunger 46 outwardly and disengaging the rack 39 so that the bolt may be retracted by the further rotation 25 of the gear 8.

In order to limit the outward projection of the bolt and to further insure the locking of the same against tampering, the gear 36 may be provided with means adapted to 30 engage the gear 37 upon the forward movement of the bolt and with the gear 35 upon the retraction of the main bolt. This locking mechanism as illustrated herein comprises a member 53 carried upon an arm 54 which may be secured to the gear 36 by 35 screws or rivets or in any other suitable manner. The member 53 may be at one end in the form of a rack 55 adapted to engage the teeth of the gear 35 when moved in one direction and at the other end with a tail piece 56 adapted to engage the gear 37 when rotated in the opposite direction so that when the train of gears is actuated by the master key to unlock the main bolt the tail 56 will 40 be thrust into engagement with the teeth of the gear 37 thus limiting the retraction of the bolt and thereby insuring the positioning of the key slot 10 in proper position. On the other hand when the main bolt 3 is 45 advanced by the master key in the manner aforesaid the bolt will be projected until the rack 55 engages the teeth of the gear 35 whereupon further rotation of the train of gears will be arrested since the gears 35 and 50 56 intermesh and at this time the rack 55 will prevent relative rotation of said gears. The intermeshing of the rack 55 with the gear 35 occurs simultaneously with the release of the plunger 46 by the sharply inclined surface 51 of the cam 49 so that when 55 the bolt is projected the gear train which operates the same is doubly locked against rotative movement.

It will be observed that the gear train 34, 60 35, 36, 37 and 38 which approximately en-

compasses half the circumference of the main gear 28 opposite to the main train thereof which engages the rack will serve to maintain the main gear in its proper position and give rigidity thereto. In order to 70 likewise more securely brace the gear 29 which actuates the auxiliary lock, and to provide means whereby different keys may be used also to actuate the auxiliary lock, I have provided two gears 57, 58 journaled 75 upon hollow spindles 59, 60 located intermediate of the peripheries of the gears of the main train, the gears 57, and 58 meshing with the gear 29 which actuates the auxiliary lock. These gears 57 and 58 may be 80 provided with slots 61, 62 differing in form from each other and each differing from the slot 30 in the gear 39 so that different keys may be given to different employees each of which may be adapted to unlock the auxiliary bolt but none of which is capable of actuating the main lock.

In order to provide for the actuation of the main lock from the opposite side of the door, without permitting the key to pass 90 through the door, the pivot 9 of the gears 8 and 29 may be provided with a central solid portion 63 and a cylindrical extension 64. A disk 65 rotarily mounted in a cylindrical recess 66 in the outer face of the casing 1 95 may be provided with a slot 110 corresponding to the slot 10 of the gear 8 and a cover plate 67 with a suitable slot 68 conforming to the form of the bit 33 of the key may be provided to cover the disk 65 so that the 100 disk 65 can only be rotated when the key is thrust through the slot into engagement with the disk and stud 64 whereby the gear 8 may be rotated in the manner aforesaid. If desired the stems 59, 60 of the gears 57 and 105 58 may likewise be extended through the plate 1 and provided with suitable disks similar in character to the disk 65 by which the gears 57, 58 may be rotated from the opposite side of the lock to actuate the auxiliary bolt 4. This feature however is illustrated in dotted lines and it will be obvious that the construction may be easily and readily made. In such case the cover plate 110 67 will be of sufficient size to inclose all of the disks necessary to the actuation of the lock from the opposite side of the door to that which was first described.

It will be obvious from the above description that this lock is adapted to a variety of uses. For example if used as the lock of a safe, in which case access to the lock from one side only is necessary, the proprietor may retain possession of the master key, permitting trusted employees to have different keys, three in number so that each of the employees may have access to the safe so long as the main bolt has been withdrawn by the master key. The auxiliary keys however 125 will be powerless if the main bolt has been 130

shot by the master key. In case the lock is to be used under conditions where it is to be accessible from both sides, two different keys may be given to others, while the master key remains in the hands of the proprietor. It will also be obvious that by using additional gears in the train which operates the supplemental lock to connect with the gearing train which actuates the main bolt, means may be provided whereby one or more of the supplemental keys may also be used to actuate both the main and auxiliary bolts. This will be particularly useful where packages are to be shipped under lock from one place to another in which case the main or master key may be retained in the hands of the proprietor and a different key placed in the hands of the party who is to receive the package.

While I have thus described a selected embodiment of my invention it will be obvious that other embodiments may be made by those skilled in the art without departing from the spirit and scope of my invention as illustrated in the drawings and more particularly pointed out in the claims hereto annexed.

Having thus described my invention what I claim as new and desire to secure by Letters Patent is:

1. A lock comprising a plurality of locking bolts, independently operable racks and gears for actuating said bolts and means adapted to cause the actuation of both said bolts in unison.
2. A lock comprising a plurality of locking bolts, independently operable means for actuating one of said bolts and a master key adapted to cause the actuation of both said bolts in unison and means operable by said master key for locking said bolts in projected or retracted position.
3. A lock comprising a main locking bolt and an auxiliary locking bolt, means including racks and gears for actuating both bolts in unison from a master key, means for actuating the auxiliary bolt by an auxiliary key independently of the main bolt when the latter is retracted and means operable by the master key for locking the main bolt in retracted position whereby the actuation thereof by the auxiliary key is prevented.
4. A lock comprising a main locking bolt, an auxiliary locking bolt and means for actuating the said bolts including racks and gears, the auxiliary lock being operable by an auxiliary key and both locks being operable simultaneously by a master key.
5. A lock comprising a main locking bolt, an auxiliary locking bolt and means for actuating the said bolts including racks and gears, the auxiliary lock being operable by an auxiliary key and both locks being operable simultaneously by a master key and means for retaining the gear which actu-

ates the main bolt from rotation when the latter is retracted, whereby the auxiliary bolt may be operated independently of the main bolt.

6. A lock comprising a main locking bolt and an auxiliary locking bolt, a train of gears for actuating the main bolt, one of said train engaging a rack upon said bolt, an auxiliary gear mounted upon the same axis with the gear which engages the main bolt and engaging a rack upon the auxiliary bolt and means operable by the rotation of the gear for actuating the main bolt adapted to engage the gears of said train and lock the same against rotation.

7. A lock comprising a main locking bolt and an auxiliary locking bolt, a train of gears for actuating the main bolt, one of said train engaging a rack upon said bolt, an auxiliary gear mounted upon the same axis with the gear which engages the main bolt and engaging a rack upon the auxiliary bolt, a pivotally and slidably mounted rack operable by one of the gears of said train, means for causing said rack to engage two intermeshing gears to lock the same and for disengaging the rack from one of the gears of said train.

8. A lock comprising a main locking bolt and an auxiliary locking bolt, a train of gears for actuating the main bolt, one of said train engaging a rack upon said bolt, an auxiliary gear mounted upon the same axis with the gear which engages the main bolt and engaging a rack upon the auxiliary bolt and means operable by the rotation of the gear for actuating the main bolt adapted to cause the interlocking of the gears of said train comprising a rack slidably mounted upon a pivoted guide, resilient means normally adapted to press the rack into engagement with a plurality of gears, a plunger engaging said pivoted guiding means and a cam upon the main bolt actuating gear adapted to cause the disengagement of the rack from one of the gears of said train upon rotation of said main bolt engaging gear.

9. A lock comprising a main locking bolt and an auxiliary locking bolt, means for actuating said bolts in unison and a plurality of means operable from the same side of the lock for actuating the auxiliary bolt independently of the main bolt.

10. A lock comprising a main locking bolt and an auxiliary locking bolt, means for actuating said bolts in unison and a plurality of means for actuating the auxiliary bolt independently of the main bolt consisting of a train of gears each of said gears being operable by a key of different form from that of the others.

11. A lock comprising a main and auxiliary bolt, means for actuating the same simultaneously by a master key, means for

actuating the auxiliary bolt independently of the main bolt, a latch carried by the auxiliary bolt, an actuator therefor, a knob and means for removing the actuator for the latch from operative relation to the knob when the auxiliary bolt is projected.

12. A lock comprising a locking bolt, a latch carried by said bolt and movable relatively thereto, an actuator for said latch, a handle member adapted rotatively to engage said actuator and means operable upon the projection of the bolt to disengage said actuator from said knob member.

13. A lock comprising a bolt having a channel shaped recess, a latch slidably mounted in said recess and having parallel arms, a rotatable actuator having means adapted to engage said arms and move the latch relatively to the bolt, a knob member normally in operative connection with said

actuator and means for projecting said bolt whereby said actuator will be withdrawn from operative relation to said knob member.

14. A lock comprising a locking bolt having a channeled portion, a latch having rearwardly extending arms slidably mounted in said channel, a spring adapted normally to maintain the latch in projected position, an actuator having cam projections engaging said arms, a gear upon said actuator, a knob member having a gear adapted to engage the gear upon said actuator, means for projecting said bolt whereby the gear upon the actuator will be removed from relative engagement with the gear upon the knob member.

In testimony whereof, I have signed my name to this specification.

LIBORIO G. GIARDINO.
